EDWARD J. STECKLE, OF EL PASO, TEXAS.

PULVERIZING OR GRINDING MACHINE.

1,092,302.

Specification of Letters Patent. Patented Apr. 7, 1914.

Application filed July 26, 1913. Serial No. 781,423.

To all whom it may concern:

Be it known that I, EDWARD J. STECKLE, a citizen of the United States, residing at El Paso, in the county of El Paso and State of Texas, have invented a new and useful Pulverizing or Grinding Machine, of which the following is a specification.

This invention has reference to improvements in pulverizing or grinding machines, 10 and its object is to provide means whereby the output of the pulverizing mill may be largely increased.

In accordance with the present invention air is exhausted from the pulverizer or grinding 15 mill, carrying with it an amount of pulverized material, and this air stream, caused by a suitable fan, is directed into a separator, which may be of the cyclone type, and the air freed from the pulverized material 20 is returned to the pulverizing or grinding zone of the mill, and in this return pipe there is provided a valve vent acting as a relief for surplus air. In order to establish an induced draft through the mill the outlet 25 pipe or duct therefrom leading to the usual conveyer for the pulverized material has connected thereto an auxiliary pipe which may be of less diameter than either the outgoing or inflow pipe for air, and this auxiliary pipe is connected to the suction duct 30 or pipe close to the fan. Moreover, the collecting member of the cyclone separator is arranged for discharge into the conveyer receiving pulverized material from the mill. 35 The present invention has been found in practice to be especially useful in connection with pulverizing limestone and cement clinker, and practice has demonstrated that it increases the output of the mill nearly or 40 quite one hundred per cent., and, furthermore, gives a finer product than heretofore, such fine product being very desirable in the manufacture of Portland cement and other materials that require fine grinding.

45 The invention has to do particularly with pulverizing machines using screens for separation, and as nearly every such mill requires fineness of ninety per cent., passing a two hundred mesh screen, it has been found impossible to get more than about one-half of the grinding capacity of the mill through the screens, particularly if the material be slightly damp. The present invention relieves the mill of all dampness and takes care

of the surplus material, while the returned 55 air causes a constant agitation in the grinding zone of the mill, and this increased agitation gives larger output.

The invention will be best understood from a consideration of the following detailed 60 description taken in connection with the accompanying drawings forming part of this specification, with the further understanding that while the drawings show a practical form of the invention, the latter is not 65 confined to any strict conformity with the showing of the drawings, but may be changed and modified so long as such changes and modifications mark no material departure from the salient features of the invention. 70

In the drawings there is shown partly in elevation and partly in section an arrangement embodying the present invention, some parts being in section and broken away and supporting members being omitted. 75

Referring to the drawings there is shown a grinding or pulverizing mill 1 which in its particular structure forms no part of the present invention, and may be the same or similar to the pulverizing or grinding 80 mill shown in United States Patent No. 922,496, granted to J. W. Fuller, Jr., on May 25, 1909, but it is to be understood that the present invention is not limited in use to the mill illustrated since the invention 85 may be adapted to other mills.

On top of the mill 1 and communicating with the pulverizing chamber is a separation chamber 2 from which there leads a pipe 3, and this pipe because of its function may 90 be termed a suction pipe. The end of the pipe 3 remote from the chamber 2 communicates with the intake of a fan 4 or other device of like character designed to produce subatmospheric pressure within the pipe 3, 95 and thereby cause a current of air therein from the separation chamber 2 to the fan 4.

The outlet side of the fan is connected by a pipe 5 to a separator 6 which may be of the cyclone type and follow any desired 100 form of such separator adapted to the purpose of the present invention, or it may be indicative of any other type of separator suited to the invention. The separator 6 is shown as provided with a collecting hopper 105 7, and leading from a high point in the separator is a pipe 8 carried to the pulverizing machine 1 and entering the pulveriz-

ing chamber thereof as indicated at 9, the arrangement being such that the inflowing stream of air will cause more or less agitation of the material within the pulverizing chamber.

At any suitable point in the pipe 8 there is located a vent pipe 10 provided with a valve 11 which may be arranged to permit the escape of air from the pipe 8 to the atmosphere, and thus regulate the amount of air directed by the return pipe 8 into the mill 1.

Pulverulent material from the mill 1 finds escape by gravity through a discharge pipe 12 leading into a conveyer 13 by means of which the material may be moved to any suitable point of disposal. Connected to the discharge pipe 12 is an auxiliary pipe 14 having a gently curved portion 15 where entering the pipe 12, and this auxiliary pipe 14 leads to the pipe 3 which it enters by a gently curved portion 16 opening into the pipe 3 in substantially the direction of flow of air through this pipe toward the fan 4.

The hopper 7 serving as a collector for fine material carried by the air into the separator 6 is connected by a pipe 17 to the conveyer 13.

The fan 4 is driven by power in any suitable manner and is arranged so that the velocity of air in the pipe 3 may be regulated as desired.

The grinding machine of the character illustrated in the drawings is one using screens for separation. Not only is the air within the mill agitated, but a certain proportion of the fine material is carried by the air stream through the pipe 3 and pump or fan 4 into the separator 6 in which the fine material is deposited from the air. The degree of fineness of the material carried by the air depends upon the velocity of the latter and this may be regulated to a nicety by driving the fan 4 at such speed as will establish the desired flow of air, different speeds of the fan meaning different speeds of flow of the air through the pipe 3.

The speed of the fan 4 will depend upon the specific gravity of the material being treated and the desired fineness of the product, so that no particular directions can be given for the speed of the fan.

The return pipe 8 enters directly into the top of the mill and is for the purpose of replacing some of the air that has already been removed and increase the circulation inside of the mill proper, besides assisting in forcing material through the screens, which material finds its way through the outlet pipe 12 and into the conveyer 13.

The auxiliary pipe 14 which may be smaller than the other pipes and connecting the discharge spout of the mill to the suction pipe close to the fan, causes an induced draft through the screens and mill and par-

tially offsets the suction from the mill to the fan. This has a tendency to keep the material in the bottom of the grinding zone of the mill and has been found to greatly increase the output of the mill.

The dust collector comprising the separator 6 with its termination 7 or any other type of dust collector suited for the purpose of the present invention is for the purpose of delivering the fine material extracted from the mill by the fan to the conveyer where it may mix with the fine material reaching it directly from the mill.

With such an arrangement actual practice has shown an output of six tons per hour with a fineness of from eighty-nine to ninety passing through a two hundred mesh screen as against from three to three and one-half tons of a fineness of eighty-four to eighty-five passing through a two hundred mesh screen, but without the exhaust system of the present invention, although treating the same material in the same factory.

What is claimed is:

1. The combination with a pulverizing mill having means for exhausting air together with fine material from the pulverizing chamber above the pulverizing elements and for returning the air freed from the fine material to the pulverizing chamber of the mill above the pulverizing elements, of means below the pulverizing elements for the escape by gravity of pulverized material from the mill, and means for directing the fine material extracted from the air exhausted from the mill to the material escaping by gravity from the mill.

2. The combination with a pulverizing mill having means for exhausting air together with fine material therefrom, of an outlet for the escape of material from the mill by gravity, and an auxiliary air exhaust duct between the intake side of the air exhausting means and the outlet of the mill provided for the escape of material therefrom by gravity.

3. The combination with a pulverizing mill having an outlet for the escape of pulverized material therefrom by gravity, of an air duct communicating with the pulverizing chamber of the mill, an air exhausting means connected with the air duct, a dust collector into which the air exhausting means discharges, an air pipe leading from the dust collector to the pulverizing chamber of the mill, and an auxiliary air pipe leading from the outlet for the escape of material from the mill by gravity to the intake side of the air exhausting means.

4. The combination with a pulverizing mill having an outlet for the escape of pulverized material therefrom by gravity, of an air duct communicating with the pulverizing chamber of the mill, an air exhausting means connected with the air duct, a dust

collector into which the air exhaust means discharges, an air pipe leading from the dust collector to the pulverizing chamber of the mill, and an auxiliary air pipe leading from the outlet for the escape of material from the mill by gravity to the intake side of the air exhaust means, said auxiliary air pipe communicating with the discharge side of the mill and with the intake 10 side of the air exhausting means by gentle curves.

5. The combination with a pulverizing mill, of a discharge duct for the escape of material from the mill by gravity, means 15 for exhausting air from the pulverizing chamber of the mill and from the discharge duct, and means for directing air under pressure to the pulverizing chamber of the mill.

20. 6. The combination with a pulverizing mill, of a discharge duct for the escape of material therefrom by gravity, an air exhaust duct communicating with the pulverizing chamber of the mill, an air exhaust 25 duct communicating with the said discharge duct of the mill, air exhausting means having common communication on the intake side with both air exhaust ducts, and means for directing air from the pressure side of

the air exhaust means to the interior of the 30 pulverizing chamber.

7. The combination with a pulverizing mill, of means for exhausting air from above and below the pulverizing elements of the mill, and means for introducing air 35 under pressure into the mill at a point above the pulverizing elements of the mill.

8. The combination with a pulverizing mill, of means for exhausting air from the mill both above and below the pulverizing 40 elements, means for the escape of material from the mill by gravity, means for separating from the air withdrawn from above the pulverizing elements the fine material thereby exhausted from the mill, means for 45 delivering fine material so separated to the material escaping from the mill, and means for directing the clean air under pressure to the pulverizing chamber above the pulverizing elements. 50

In testimony, that I claim the foregoing as my own, I have hereto affixed my signature in the presence of two witnesses.

EDWARD J. STECKLE.
